UNITED STATES PATENT OFFICE.

BENJ. F. DAY, OF PHILADELPHIA, PENNSYLVANIA.

STEAM-ENGINE.

Specification of Letters Patent No. 11,119, dated June 20, 1854.

To all whom it may concern:

Be it known that I, BENJAMIN F. DAY, of the city and county of Philadelphia and State of Pennsylvania, have invented certain new and useful Improvements in Steam-Engines; and I do hereby declare the following to be a full, clear, and exact description of the same, reference being had to the accompanying drawings, making a 10 part thereof, and in which—

Figure 1 represents a perspective view of the engine. Fig. 2 represents a view on top of the steam chests, with the lids or covers thereof removed, to show the valves therein. 15 Fig. 3 represents a top view taken underneath the steam chests, so as to show the steam ports and passages. Fig. 4 represents, a longitudinal vertical section through the expansion cylinder, with the valves in their 20 places, and showing the steam and eduction passages of said expansion cylinder. Fig. 5 represents, a vertical transverse section through the cylinders and steam chests, showing the passages leading out of the ports of 25 the receiving cylinder, into the steam chests on the expansion cylinder. Fig. 6 represents the valves, &c., detached from their places.

I am aware that many attempts have been 30 made to work over by expansion, the steam escaping from one cylinder, in another cylinder, both being so arranged as that their piston rods shall connect with the same crank shaft. I make no pretension to originality of invention in the principle of such economical working of steam. But the radical 35 defects, in the details, for carrying out this principle, have thus far prevented such engines from coming into general or practical use. Among the prominent defects in the application of this principle, may be mentioned that, of keeping open a free communication between the cylinders, or allowing the steam to pass immediately from one cylinder to the other, through passages or openings leading direct from one to the other. Another defect is, in the attempt to make one exhaust passage common to both cylinders. By both the plans, the action of the 40 expansion cylinder, is entirely dependent upon that of the receiving cylinder, and only about half a cylinder full of steam can be used expansively in the second cylinder; or rather, it can only act on the piston of the 45 second or expansion cylinder during one half of its stroke, as the return of the piston 50

in the receiving cylinder, opens the direct communication between them, and the steam in the expansion cylinder must exhaust. So also, in the latter case, where there is one exhaust common to both cylinders, for they must of course exhaust at the same time, and in the plans suggested for this construction, the steam from the expansion cylinder is made to exhaust back through the receiving cylinder to the eduction pipe, and this requires such uniformity of motion of both pistons, as to make the receiving cylinder control the expanding cylinder, not giving the steam in the second cylinder time to act to its full extent expansively, for the piston of the expanding cylinder can only receive the action of the steam expansively for about one half of its stroke, since it must exhaust at a fixed time to conform with the return of the piston in the receiving cylinder. Now, to work the steam by its direct action in a second cylinder, is not economical, for it can be done as advantageously in one cylinder, and at less cost of construction. The second cylinder is therefore designed for working the steam escaping from the first cylinder expansively, yet, as I have shown, the means heretofore devised, only admit of such expansive action, during one half of the stroke of the piston. It is therefore clear that a direct communication or steam-way between the cylinders, embarrasses the action of the second or expanding cylinder, and the expansive force of the steam therein to a great extent is lost.

The nature of my invention consists in taking the steam, from the first cylinder, which is to be worked expansively in the second one, to a steam chest suitably provided with valves, ports, and passages, so that it may be let on to the second cylinder, act, and exhaust therefrom by the action of the said valves and ports, without being influenced to so great an extent, as heretofore, by the return of the piston of the first cylinder, which is the case where the communication is direct from one cylinder to the other. This method of applying the steam to the second cylinder, allows it to act expansively on its piston, during the whole of its stroke, effecting a saving over the other methods of one third.

The second part of my invention consists in the inclosing of the expansion cylinder in a jacket or second cylinder so as to leave a flue space between them, through which

a current of heated air, or gases, is allowed to pass, for the purpose of reheating the steam in said expansion cylinder, and causing it to act with more effect on the piston.

5 And I would here remark that, I only lay claim to the reheating of the steam when it is to be used expansively in a second cylinder, premising that to do so in a receiving cylinder, would be only taking heat from 10 the boiler to apply it elsewhere, where it could not effect my special good result. But in the second cylinder where steam has lost a portion of its elastic force, by its passage through the first cylinder, and the steam 15 chests and passages, the restoring to it, by heating its cylinder, a portion of its lost heat, renders it more effective and economical.

To enable others skilled in the art to 20 make and use my invention, I will proceed to describe the same with reference to the drawings.

Before entering into the more minute description of the accompanying drawings, I 25 would state that, the receiving engine may be constructed in any of the well known forms of high pressure or noncondensing engines, and I shall not therefore, make any farther reference to that part of the 30 engine than is merely necessary to explain its connection with the other part of the engine upon which my improvement is especially applicable.

The communication between the boiler 35 and the engine is by means of the pipe A, leading directly into the steam chest B, from whence the steam is admitted through the passages C, C, alternately, into the receiving cylinder L, by a simple slide valve 40 a, Fig. 2, moved by an eccentric b, on the rock shaft M, (Fig. 1,) and a strict regard to economy will require it to be made so as to cut off the steam at or about half stroke. The steam being admitted into the receiving 45 cylinder L, it is also conducted by the transverse passages D, D, (in dotted lines Fig. 3, and in section Fig. 4,) leading out of the passages C, C, into the steam chest E, on the expansive cylinder N, the crank O, of 50 the receiving engine having arrived on the half center, thus bringing the crank P, of the expansion engine on its center. The valves F, F, now commence opening the ports G, leading into the expansion cylinder, when the steam is worked expansively 55 in both cylinders at the same time until the receiving engine has finished its stroke. The steam contained in the receiving cylinder is then allowed to escape by the education pipe I, and that portion of the steam 60 remaining in the expansion cylinder comprising about one third of the whole, is retained by the valves H, closing the ports D, and it continues to work expansively until 65 the end of the stroke of the expansion en-

gine, when it escapes by the education passages K, K, thus using the same steam during three fourths of the revolution and on both the half centers at which the greatest power is imparted to the shaft owing to 70 the greater leverage.

The valves F, of which Fig. 6, represents views of the side, bottom and top, are moved by a crank motion from the rock shaft M', through the arm e, and rod d, and are placed inside of the arms of the valves H H, also represented in Fig. 6, and motion is communicated to the valves H, H, by the valves F, F, coming in contact with them, alternately as they are moved by their rod d. The rock shafts M, M', apparently one in the drawing, though really two, may have a step either in one or the other, so that they may have separate movements. Or they may be hollow resting on a fixed bar, so that the one M, may be operated by the eccentric e, on the crank shaft, and the other M', by the eccentric f, also on said crank shaft, but admitting of motions entirely independent of each other. 80

The expansion cylinder N, is surrounded by a jacket or second cylinder Q Figs. 1, 5, leaving a flue space R, between said cylinders, through which heated air or the heated product of combustion from the furnace may pass, as indicated by the arrows Fig. 5, and said flue should also be provided with a damper s, having a handle g (Fig. 1,) thereto, for regulating the quantity of heat to be admitted. 90

In Fig. 1, T represents the inlet for, and U, the exit of, the heated products, after they have passed entirely around the cylinders, and h represents the exhaust from the expansion cylinder, which may be made into said flue, for the purpose of increasing the draft through it. The object in passing this current of heated air around the expansion cylinder, is for the purpose of restoring to the steam therein a portion of the heat abstracted from it by its passage through the various ports, or openings by radiation and the expansion and to increase thereby the effective force of the steam in said cylinder. The heat used may be the 100 waste heat from the furnace, or from any other source. 105

Having thus fully described the nature of my invention I would state that I lay no claim to the double engine connected to 110 cranks at right angles on one shaft; neither do I claim the principle of using steam expansively in connection with a cylinder or engine using it directly from the boiler, as these are described in the patent granted to 115 Daniel Barnum on the 19th Sept., 1846; neither do I claim the arrangement of valves as patented to said Barnum. But

What I do claim as my invention and desire to secure by Letters Patent is— 120

In contradistinction from allowing the steam to pass directly from one cylinder to the other, the taking of the steam from the receiving cylinder to a steam chest provided with valves and ports, by and through which the steam is admitted to, and exhausted from the expansive cylinder, by

which means I retain a longer expansive action of steam, substantially as described.

B. FRANKLIN DAY.
